(57) **CLAIM**

The ornamental design for an electric rodent trap, as shown and described.

DESCRIPTION

FIG. 1 is a front perspective view of an electric rodent trap showing the claimed design.

FIG. 2 is a rear perspective view thereof.

FIG. 3 is a front view thereof.

FIG. 4 is a rear view thereof.

FIG. 5 is a right side view thereof.

FIG. 6 is a left side view thereof.

FIG. 7 is a top view thereof; and,

FIG. 8 is a bottom view thereof.

The broken lines shown in the drawings are included for the purpose of illustrating environment and form no part of the claimed design.
